UNITED STATES PATENT OFFICE.

JOSEPH NÉREE GINGRAS, OF THETFORD MINES, QUEBEC, CANADA, ASSIGNOR OF ONE-HALF TO WILSON W. BUTLER, OF MONTREAL, CANADA, ONE-SIXTH TO LUCIEN T. PACAUD, OF THETFORD MINES, CANADA, AND ONE-SIXTH TO WILLIAM J. LYNCH, OF QUEBEC, CANADA.

GRAIN-DOOR.

1,211,309.

Specification of Letters Patent.

Patented Jan. 2, 1917.

Application filed November 21, 1912. Serial No. 732,709.

To all whom it may concern:

Be it known that I, JOSEPH NÉREE GINGRAS, a subject of the King of Great Britain, residing at Thetford Mines, in the Province 5 of Quebec, Canada, have invented certain new and useful Improvements in Grain-Doors; and I do hereby declare that the following is a full, clear, and exact description of the same.

10 This invention has for an object to provide a grain door of greater simplicity than those heretofore used and which will permit of a more rapid discharge of the grain.

A further object is to provide a door of 15 this type which will be easily applicable to ordinary box cars; which will present no permanent obstructions adjacent the door opening, and of which certain parts may be employed to protect the ordinary door casing 20 of the car from injury when the grain door is not in use.

A still further object is to construct the door in a manner to render it difficult or 25 impossible for the grain shipper to nail it in place.

For further comprehension however of the invention and of the objects and advantages thereof reference will be had to the following description and appended claims 30 and to the accompanying drawings forming part of this specification in which similar reference characters indicate the same parts and wherein:

Figure 1 is a face view of a grain door 35 embodying my invention showing it in position in the car door opening and looking from the interior of the car. Fig. 2 is a transverse vertical section on the line 2—2 Fig. 1. Fig. 3 is a horizontal section on 40 the line 3—3 Fig. 1. Fig. 4 is a perspective view of one side of the door frame showing the door post strip turned inwardly. Fig. 5 is a perspective view of the door, taken from the outside of the car, and showing it 45 falling outward after the retaining means has been unlocked. Fig. 6 is a view similar to Fig. 3 of a modification.

In the drawings I have shown my improved grain door applied to a box car 50 of ordinary construction, the side of the car being indicated at 1 and the roof and flooring at 2 and 3 respectively. The casing of the usual side door opening is shown at 4, and the door opening (the lower portion

of which is adapted to be closed by the grain 55 door) is indicated by the reference numeral 5.

The grain door proper is shown at 7 and may be of any suitable detail construction, being here shown as comprising cross boards 60 reinforced by the battens 8. This door is adapted to be placed within the door opening 5, being of less width than the latter, and to retain it in place and form a tight joint between the sides thereof and the adjacent sides of the permanent door casing 4 removable or adjustable door post strips or door retaining strips are provided which are mounted upon the casing 4 and engage the sides of the door 7. These adjustable 65 door post strips, are preferably formed of angle bars one flange 9 whereof is turned inwardly toward the interior of the car and rests in flat contact with the face of the door casing 4 while the other flange 9' 70 projects into the door opening and overlaps the sides of the grain door on the outside thereof and supports it against outward movement, the strips being adjustably retained in place by suitable means. The retaining means which I have devised and here illustrated comprise a pair of staples 75 10 fixed to the door casing 4 one on each side of the door opening and upon which the strips are freely hung, the upper ends 80 of the inturned flanges 9 being formed to present short vertical slots 11 through which the staple legs pass. This slot and staple connection forms a universal joint by which the door post strips are secured to the frame 85 4 to permit of the strips swinging in different directions for a purpose to be presently pointed out.

The lower ends of each of these door post strips is retained in position by inner and outer detent latches, 15 and 16 respectively, hinged as at 15' and 16' in vertical grooves 17, 18 in the casing 4 and adapted to project across the outer and inner sides respectively of the door post strips, the inner latches 16 100 being located somewhat higher than the outer latches 15 and adapted also to prevent the grain door from falling inward when the car is empty.

When the car is to be unloaded one of the 105 latches 16 is thrown upward leaving the lower end of the post strips free and allowing the weight of the grain to throw the

door outward, the angle bar swinging freely outward also.

- When the car is to be used as an ordinary box car the latches 15, 16 are thrown upward and lie entirely concealed within the grooves 17, 18 and out of the way of objects passing through the door opening. The strips 8, 9 are also turned inwardly to the position shown in full lines in Fig. 4 in which they cover the inner corners of the door casing 4 and are not only out of the way but also serve to protect the door casing from injury. The universal connection between the upper ends of the strips and the casing, which has been described above, permits both the outward swinging of the strips to release the grain door and the inward turning to the position shown in dotted lines in Fig. 4.
- As shown in the drawings small angular lugs 19 may be provided on the car floor adjacent the inner corners of the door casing to engage the lower ends of the strips and retain the latter in their inturned position, the slots 11 permitting the strips to be raised sufficiently to clear the lugs when moved from one position to the other.

When the grain door is not in use it may be hung in any convenient manner within the car being preferably permanently attached thereto by a loose chain 20 to prevent its removal.

In Fig. 6 I have shown a modification in which only one of the adjustable door post strips is employed, the opposite side of the grain door being retained in a groove or recess 25 formed in any suitable manner in the door casing. When the latch 16 is released the side of the door will swing out in the same manner as shown in Fig. 5.

What I claim is as follows:

1. In a car having a door opening, a strip formed of angularly disposed flanges and being adapted to inclose the lower portion of the inner corner of one of the side posts of such door opening, one flange of the strip overlapping that surface of the side post which faces inwardly of the car and the other flange of the strip overlapping that surface of the mentioned side post which faces inwardly of the door opening and means for hinging the strip to said door post whereby the strip may be swung into the door opening to a position with one flange flat against the post and the other flange projecting from the post into the door opening.
2. In a car, the combination with a grain

door, of a door post strip adapted to engage the side of the grain door, and means providing a universal joint connection between the upper end of such strip and the car to permit of the strip being moved in different directions out of the position wherein it is adapted to engage with the door, for the purpose set forth.

3. In a car, the combination with a door casing presenting a door opening, of a grain door, a door post strip within the door opening adapted to engage the side of the grain door, releasable means retaining the lower end of the said strip in position, and means providing a universal joint connection between the upper end of such strip and the door casing to permit of the lower end of the strip being swung bodily outward when the said locking means is released, or the strip being swung around the door casing out of the position wherein the strip is adapted to engage with the grain door.

4. In a car, the combination with a door casing presenting a door opening, of a grain door, a door post strip within the door opening adapted to engage the side of the grain door, releasable means retaining the lower end of the said strip in position, and including a detent latch pivotally mounted in the car and adapted to project across the face of the door, and means providing a universal joint connection between the upper end of such strip and the door casing to permit of the lower end of the strip being swung bodily outward when the said locking means is released, or the strip being swung around the door casing out of the position wherein the strip is adapted to engage with the grain door.

5. In a car, the combination with a grain door, of a pair of door post strips of angular cross section adapted to engage the sides thereof, slot and staple connections between the upper end of such strips and the car, whereby the strip may be swung in different directions out of the position wherein it is adapted to engage with the door, and detent latches pivoted adjacent such strips and adapted to project across the inner and outer sides thereof.

In testimony whereof, I have signed my name to this specification, in the presence of two subscribing witnesses.

JOSEPH NÉREE GINGRAS.
